COMBINED TOOTHPASTE DISPENSER AND TOOTHBRUSH HOLDER

Daniel R. Kalosky, 2439 Donald Ave., Youngstown, Ohio

Filed Apr. 12, 1965, Ser. No. 84,731

Term of patent 14 years

(Cl. D4—3)

The back not shown is substantially plain.

I claim:

The ornamental design for a combined toothpaste dispenser and toothbrush holder, as shown and described.
